Harry C. Adams

INVENTOR.

UNITED STATES PATENT OFFICE.

HARRY C. ADAM, OF ST. LOUIS, MISSOURI.

DESIGN FOR A LIGHTING-FIXTURE.

57,563.

Specification for Design.

Patented Apr. 26, 1921.

Application filed September 20, 1920. Serial No. 411,676. Term of patent 14 years.

To all whom it may concern:

Be it known that I, HARRY C. ADAM, a citizen of the United States, residing at St. Louis, Missouri, have invented a certain new, original, and ornamental Design for a Lighting-Fixture, of which the following is a specification, reference being had to the accompanying drawing, forming a part thereof.

The drawing is a side elevational view of my new ornamental design for a lighting fixture.

I claim:

The ornamental design for a lighting fixture, as shown.

HARRY C. ADAM.
